UNITED STATES PATENT OFFICE.

VERNON C. TASKER, OF WASHINGTON, DISTRICT OF COLUMBIA.

BREECH-LOADING ORDNANCE.

SPECIFICATION forming part of Letters Patent No. 599,482, dated February 22, 1898.

Application filed November 17, 1897. Serial No. 658,827. (No model.)

To all whom it may concern:

Be it known that I, VERNON C. TASKER, a citizen of the United States, residing at Washington, in the District of Columbia, have invented certain new and useful Improvements in Breech-Loading Ordnance; and I do hereby declare the following to be a full, clear, and exact description of the invention, such as will enable others skilled in the art to which it appertains to make and use the same.

My invention consists of a breech mechanism for use on guns having what is known as the "slotted-screw system of breech-closure," and is of that particular class in which the breech-block after being disengaged by a partial rotation from the threads of the breech is adapted to immediately swing clear thereof about a hinge on the gun without being previously retracted in a straight line.

I shall here describe my invention in the best form known to me at present and as applied to a gun of small caliber; but it should be understood that it is susceptible to improvement in forms, proportions, and details of construction, (and to desirable additions,) especially in its application to guns of large caliber, by the exercise of ordinary mechanical skill and without departing from the spirit of the invention.

Reference is had to the accompanying drawings, in which the same parts are indicated by similar letters throughout the several views.

Figure 1 represents a horizontal section of the gun and of the mechanism in the closed position. Fig. 2 is a rear elevation of the same. Fig. 3 is a rear elevation with the breech open. Fig. 4 represents a horizontal section of the parts with the breech open.

Fig. 5 represents a vertical longitudinal section of the gun and mechanism. Fig. 6 is a side elevation of the hinged side of the same. Fig. 7 shows a rear view of the breech-block as detached from the gun. Fig. 8 represents a longitudinal section of the breech-block, showing the cocking-pin therein and a part of the firing-pin with the cam-surface for engagement therewith; and Fig. 9 is a diagram illustrating the principle of the extraction.

Fig. 10 represents a modification of the lock-

ing device for preventing the rotation of the block. Fig. 11 shows a modification of the sear and lever-pivot.

A represents the gun, provided with teeth a , blank a' , and cut away, as at a^2 , to allow 55 the breech-block to swing out.

B represents the breech-block, provided with a central recess in its rear face.

C represents an arm or carrier for the breech-block, hinged to the side of the gun 60 and having a forwardly-projecting stud or journal J, extending into the recess in the block and having threaded engagement therewith, the threads being of even pitch and direction with those on the exterior of the 65 block, the object of this construction being to afford a rigid and secure support for the block while out of contact with the gun, whereby it may be swung clear of the breech immediately upon its disengagement therefrom; also, to accommodate the longitudinal motion accompanying the rotation of the block and to insure the perfect alinement of the locking-threads on the block with those in the gun when the carrier is swung to the 75 closed position; also, to confine the carrier C to a fixed position relatively to the gun until the block is disengaged therefrom, obviating any tendency of cramping between the carrier-stud and the interior surface of the block, as 80 from the thrust of the firing-spring against the carrier. A flange B' on the block closes all rear apertures in the breech against the entrance of dust, &c., when locked and also reinforces the block in the cut-away portions 85 thereof.

The breech-block is rotated by means of a toggle-joint, one of the links, D, of which is attached to the breech-block B near its circumference, and the other, L, is pivotally attached to the hinged carrier C, as shown most clearly in Figs. 3 and 4. As a means of operating the toggle-joint I prefer to extend the link L to form the handle H for operating the mechanism. It might also be a wheel 90 with suitable means of rotation in cases where greater power is required.

The link L, which I shall call the "lever-link," has a simple pivotal connection with the carrier C, whereby it is constrained to 100

move in a plane parallel with the bore of the gun. The link D, which may conveniently be called the "connecting-link," has at each of its ends a universal joint for connection 5 with the lever-link and breech-block, respectively, to accommodate their motions occurring in different planes. The form of universal joint most preferred by me in this application of the mechanism is a lug pivoted 10 in each end of the connecting-link D, having a cylindrical stem threaded for a portion of its length, that on one end of the connecting-link D being screwed partially into the breech-block and that on the other end similarly attached 15 to the lever-link L, as shown in Fig. 4. The threaded engagement retains the lugs in their sockets while permitting their rotation. Other forms of universal joint might be used to advantage—the well-known ball- 20 and-socket joint, for example.

It will be seen from an inspection of Figs. 1 to 4 that the first movement of the lever-link L about the pivot will be to rotate the breech-block through the requisite angle to 25 unlock the same, and then the whole system will swing about the pivot W until the breech-block is clear of the breech, as shown in Fig. 4. The object of this method of effecting the rotation of the block is to avoid the excessive 30 friction and wear incident to the use for this heavy duty of cams, sliding teeth, and other mechanical elements in which contact exists only in a point or a line and to furnish instead surfaces having a mechanical fit over 35 an appreciable area, as also to avoid refined and expensive work in the manufacture.

The centers of articulation of the toggle-joint are so disposed that in the closed position of the mechanism they have moved into 40 one straight line, being the position technically known as "dead-center" or a little beyond, as shown in dotted lines in Fig. 1, thus providing an absolute lock against the accidental rotation of the block by forces applied 45 to it direct arising from the explosion or any other cause. This arrangement also contributes great power toward the rotation of the block when near its closed position, that being its position of greatest resistance.

50 The block is provided with a boss B², which, coming in contact with the carrier C, serves as a stop against the further rotation of the block when it has become disengaged from the breech, the toggle-links limiting its rotation in the other direction.

55 A recess K in the rear face of the block, near its periphery, is so situated as to register, when the block is unlocked, with a spring-catch G, carried in the hinged carrier C, two forms of which are shown, one in the principal views and another in Fig. 10. In each the catch is prevented from entering the recess K by its contact with the gun until the carrier has swung partially away from the 55 same, when it is forced in by its spring M and

prevents any rotation of the block while out of the breech.

The firing-pin F (see Fig. 5) is provided with a cylindrical shaft or head F', preferably hollow, centrally located in the projection J 70 of the carrier and with a rearwardly-extending stem or tail F² on the same, eccentric and parallel thereto, passing through the carrier and terminating in an eye f for cocking by hand with a hook, said tail having a notch, 75 as at f', for engagement with the sear S. The firing-spring Q has a rear abutment in the carrier and acts forwardly against the central part of the firing-pin, preferably extending into the hollow thereof. At the forward part 80 of the eccentric stem F² is an inclined surface F³, facing forwardly, and in the block is a pin or stud T, which acts against the same during the rotation of the block in unlocking, retracting the firing-pin until the notch f' is 85 past the lip of the sear, which thereupon enters the same and holds the pin cocked. The cocking-pin T is arranged so as to be readily renewable. (See Fig. 5.)

The sear S, (see Figs. 2 and 5,) as preferred 90 by me, is a simple cylindrical rod adapted to rotate in a cylindrical chamber in the carrier, provided at its external extremity with a hook S' or other suitable appendage for attaching a firing-lanyard and having at its intersection 95 with the tail of the firing-pin a semicircular or other suitable cut extending partly around the same, the deepest portion of said cut serving as a lip to engage the notch P in the firing-pin and the sides thereof embracing said 100 pin, thus locking the sear in place. The sear is rotatively actuated by a spring to cause its lip to enter the firing-pin notch. A separate spring may be supplied for this purpose; but I prefer to utilize the firing-spring by having 105 it act against the notch s in the sear, as shown in Fig. 5. One means of employing a separate spring S⁰ is shown in Fig. 11, which also exhibits a modification of the position of the sear and of the form of pivot for the lever-link. 110

Vent-holes may be provided in the block, as indicated at V, Fig. 5, for the escape of gases which may reach the interior of the block in case of a possible "blow-back" from 115 defective ammunition and also to prevent cushioning of the firing-pin.

The cartridge-case extractor E, Figs. 1, 4, and 6, is situated in a slot X through the breech-wall, said slot having a curved front 120 surface Y, the center of curvature being approximately in a line extending rearward from the inner extremity E² of the extractor. The latter is adapted to roll on this curved surface, its front surface having a curve 125 whose radius is about one-half that of the curved wall of the slot and is caused to engage this curved wall by a cam-surface C' on the carrier. The principle embodied is a geometrical property of the hypocycloid curve 130

or curve generated by any point on the periphery of a circle which rolls within the periphery of a larger circle. As is well known, in the special case in which the radius of the 5 rolling circle is one-half that of the one on which it rolls the hypocycloid takes the form of a straight line, passing through the center of the larger circle, as illustrated in the diagram Fig. 11, in which b represents the fixed 10 circle and a the one which rolls therein, the successive positions of the point a^0 being indicated at a' a^2 a^3 , &c., the corresponding positions of the rolling circle being shown in dotted lines.

15 The extractor is so proportioned that the claw or nib E^2 on its inner end, which engages the head of the cartridge-case, is about in line with the curved front surface, and said claw is thus constrained to move in a 20 straight line when the extractor rolls without sliding. Sliding is prevented to any desirable extent and the extractor is retained in the slot X by a lug or lugs E^3 E^3 on the opposite sliding surfaces of the extractor near 25 the outer extremity of its curved front face, freely moving in grooves X' in the gun, as shown in Figs. 1 and 4. Said grooves should preferably be straight and lying radially to the center of curvature of the front of the 30 slot in the gun, for the lugs E^3 E^3 being nearly in the circumference of the rolling circle they practically have the property of any point therein of moving in a line through said center. The extractor having rolled to the end 35 of the curved surface in the gun may, if further movement is desired, pivot about its lugs in the guide-grooves in the position shown in Fig. 4, the claw E^2 then moving slightly out of a straight line, but only due 40 to the difference in direction of the arc subtending a small angle and the tangent thereto. On account of its rolling action, beginning 45 near the cartridge-head and acting against a succession of fulcrums more and more remote therefrom, this extractor has great power to loosen the cartridge-case and a constant increment of velocity is given thereto, thus economizing the strain on the extractor and enabling it with a minimum amount of 50 such strain and without shock to eject the cartridge-case with a low initial and a high final velocity. The extractor is provided near its outer end with a forwardly-projecting arm E^4 , lying within the slot in the gun 55 or in cheeks Z^2 , which arm is adapted to close the space between the rolling surfaces when the mechanism is in the closed position. This is for the purpose of excluding dirt, &c., and also serves to steady and guide the 60 extractor.

The guide-grooves X' in the slot X are extended at their rear, as at x' , Figs. 1 and 4, to run out of said slot, whereby the extractor may be removed in the absence of the hinged 65 carrier and its bolt W . When the latter are in position, however, the extractor-lugs are

confined thereby to the straight or guiding part of said grooves, and the extractor cannot leave its place in the slot.

The cheeks Z^2 , embracing the arm E^4 of the 70 extractor, also serve as stops to the carrier in its open position. They may obviously be formed of metal solid with the gun, as may also the hinge-lugs Z' , and the hinge-plate Z may be dispensed with, especially in large 75 guns, they being differently proportioned. The object is to here show the mechanism as it might be applied to a small gun already built.

It will also be obvious that various modifications of the several parts and of the whole might be made by any one skilled in the art, which could be used without departing from the spirit of my invention.

It has been my special aim in this invention 85 to avoid great sliding movements between the parts, especially the breech-block and parts giving motion thereto, as a condition unsuited to the exigencies of such a service, because of the possible defective lubrication, presence of grit and other well-known hindrances to easy manipulation, and to retain as far as possible the integrity of the breech-walls, breech-block, and threads on each, especially retaining adequate circumferential strength 90 in the breech-walls to resist the radial thrust of the threads on the block, also to close all apertures against the entrance of foreign matter, and in general to improve the parts and furnish adequate mechanical means for performing the various functions of a breech 95 mechanism.

I do not claim the following issue, which I am informed is the subject-matter of an interference now pending in the Patent Office: 105 "The combination, with a breech-loading gun, of the ejector-lever having a long leverage-fulcrum for starting the shell, the successively-operating shorter leverage-fulcrum for accelerating the ejection, and means for operating said levers."

Having thus described my invention, what I claim, and desire to secure by Letters Patent of the United States, is—

1. The combination of a breech-loading gun 115 having a suitably-shaped slot cut through its wall with a cartridge-case extractor mounted in said slot and adapted to make continuous rolling contact with the front of said slot, whereby a continuously-shifting pivot is secured and means for pressing forward against the outer portion of said extractor, substantially as described.

2. The combination of a breech-loading gun 125 having a slot cut through its wall with a cartridge-case extractor mounted in said slot and adapted to make rolling contact with the front of said slot, and means for pressing forward against the outer portion of said extractor, the front of said slot being of such shape that 130 the fulcrum-point of the extractor moves continuously outward and rearward during the

- operation of extracting the cartridge-case, substantially as described.
3. The combination with a breech-loading gun, provided with a slot cut through the 5 walls of the gun the front face of said slot being curved, of a cartridge-case extractor mounted in said slot and adapted to make continuous rolling contact with said curved face, and means for pressing forward against the 10 outer portion of said extractor, substantially as described.
4. The combination with a breech-loading gun, provided with a slot cut through the 15 walls of the gun the front face of said slot being curved, of a cartridge-case extractor having a curved front face mounted in said slot and adapted to make continuous rolling contact with the curved face of said slot, and means operated by the breech mechanism for 20 pressing forward against the outer portion of said extractor, substantially as described.
5. The combination with a breech-loading gun, provided with a slot through the walls thereof the front face of said slot being curved, 25 of a cartridge-case extractor having a curved front face of greater curvature than the curved face of the slot, and having a continuously-rolling shifting fulcrum, and means for pressing against said extractor and causing 30 the same to roll along said curved wall, substantially as described.
6. The combination with a breech-loading gun, provided with a slot through the walls thereof the front face of said slot being curved, 35 approximately in the form of a segment of a cylinder, of a cartridge-case extractor having a cylindrical curved front face with a radius of curvature approximately one-half that of the curved face of the slot, the said extractor 40 for rolling on said face, and means for pressing against said extractor and causing the same to roll along said curved wall, substantially as described.
7. The combination with a breech-loading 45 gun provided with a slot through the breech-wall having a cylindrical front surface, of a cartridge-case extractor lying in said slot and having a cylindrical front surface whose radius is practically one-half that of the surface 50 in the slot, and rolling on such surface, the cartridge-engaging nib of the extractor lying in the extension of its curved surface, and the center of curvature of the front surface of the slot being directly in rear of said nib, 55 whereby the same, during the rolling of such curved surfaces, describes that special form of a hypocycloid curve which is a straight line, and means for operating said extractor, substantially as described.
- 60 8. The combination with a breech-loading gun, provided with a slot through the walls thereof the front face of said slot being curved, with a substantially rectilinear groove in the sides of said slot approximately radial to the 65 curved face aforesaid, of an extractor having a curved front face of greater curvature than the curved face of the slot rolling on said face with a stud projecting into said groove, and means for actuating said extractor, substantially as described.
9. The combination with a breech-loading gun, provided with a slot through the walls thereof the front face of said slot being curved with substantially rectilinear grooves in the side faces of said slot approximately radial to the 70 curved face aforesaid, of an extractor having a curved front face of greater curvature than the curved face of the slot and adapted to roll on said face with studs projecting into said grooves, and means operated by the breech 75 mechanism for actuating said extractor, substantially as described.
10. The combination with a breech-loading gun, provided with a slot cut through the walls of the gun and having a front curved 80 face, of a cartridge-case extractor mounted in said slot and adapted to make continuous rolling contact with said curved face whereby a continuously-shifting pivot is secured, and being provided with an outwardly-projecting 85 arm, and means for pressing forward against the said arm, substantially as described.
11. The combination with a breech-loading gun, provided with a slot cut through the walls of the gun and having a front curved 90 face, of a cartridge-case extractor mounted in said slot and adapted to make continuous rolling contact with said curved face, whereby a continuously-shifting pivot is secured, and being provided with an outwardly-projecting 95 arm controlled by the breech mechanism for pressing forward against the outer portion of said extractor, substantially as described.
12. The combination with a breech-loading gun, provided with a slot through the walls 100 thereof and provided with a curved front face, of a cartridge-case extractor having a curved front face of greater curvature than the curved face of the slot and rolling continuously thereon, and being also provided with 105 an outwardly-projecting arm, and means for pressing against said arm and causing the extractor to roll continuously along said curved face, substantially as described.
13. The combination with a breech-loading 110 gun, provided with a slot through the walls thereof having a curved face, approximately in the form of a segment of a cylinder, of a cartridge-case extractor having a cylindrical curved front face with a radius of curvature 115 approximately one-half that of the curved face of the slot, the said extractor being adapted to roll on said wall, the said extractor being also provided with an outwardly-projecting arm, and means for pressing against said arm 120 and causing the extractor to roll along the curved face of the slot, substantially as described.
14. The combination with a breech-loading gun, provided with a slot through the walls 125 thereof having a curved front face, with substantially rectilinear grooves in the sides of

said slots approximately radial to the curved face aforesaid, of an extractor having an outwardly-projecting arm and a curved front face of greater curvature than the curved wall of 5 the slot and rolling on said face with studs projecting into said grooves, and means operated by the breech mechanism for pressing against said arm and causing the extractor to roll along said curved face, substantially 10 as described.

15. The combination with a breech-loading gun, having a slot cut through the walls thereof with a guide-groove in said slot opening outward, of a removable cartridge-case extractor mounted in said slot and provided with a lug engaging in said guide-groove, and removable means for normally blocking the opening into said guide-groove, substantially as described.

20. 16. The combination with a breech-loading gun, having a slot cut through the walls thereof with extractor-retaining sides, and guide-grooves in said sides opening outward, of a removable cartridge-case extractor mounted 25 in said slot and provided with lugs engaging in said guide-grooves, and removable means for normally blocking the openings into said guide-grooves, substantially as described.

17. The combination with a breech-loading 30 gun, having a slot cut through the walls thereof with parallel sides, and guide-grooves in said sides opening outward, of a removable cartridge-case extractor mounted in said slot and provided with lugs engaging in said guide-grooves, and a removable part of the breech-closing mechanism adapted to normally block the openings into said guide-grooves, substantially as described.

35 18. In a gun of the type described, the combination of the block, the hinged carrier extending into same and having a central cylindrical chamber and a recess eccentric thereto, of a firing-pin fitting both such central chamber and eccentric recess, and held and guided by the same, substantially as described.

40 19. In a slotted-screw system breech mechanism, the combination of a carrier extending into the block, of a firing-pin with a cam-surface mounted therein, and a removable pin 45 or stud in the block adapted to move against such cam-surface during rotation of the block and to cock the firing-pin, substantially as described.

45 20. In a slotted-screw system breech mechanism, the combination of a carrier extending into the block, of a firing-pin with a cam-surface mounted in said carrier and also an arm projecting rearwardly through the carrier for cocking by hand, and a removable pin or 50 stud in the block adapted to move against such cam-surface during rotation of the block and to cock the firing-pin, substantially as described.

55 21. The combination with a breech mechanism having a firing-pin and a sear lying across and rotatively engaging the same, of means

for securing such sear in the mechanism consisting of cheeks thereon embracing such firing-pin, substantially as described.

22. In a breech-loading gun, the combination with a firing-pin provided with a notch therein of a rod lying across the firing-pin, and adapted to rotate on its axis, a lip on said rod to engage the notch in the firing-pin, to hold the same cocked, and a spring tending 70 to rotate the said rod to cause its lip to engage the notch in the firing-pin, substantially as and for the purposes described.

23. In a breech-loading gun, the combination with a firing-pin provided with a notch therein of a rod lying across the firing-pin, and adapted to rotate on its axis, a lip on said rod to engage the notch in the firing-pin to hold the same cocked, and a spring tending 80 to rotate said rod to cause its lip to engage 85 the notch in the firing-pin, with means operated by hand for turning said rod and releasing the firing-pin, substantially as and for the purposes described.

24. The combination with a gun having a 90 slot through the walls thereof for the cartridge-case extractor, a dust-guard for said slot and for the extractor consisting of a bent arm integral with said extractor and normally adapted to close the outer orifice of said slot, 95 substantially as described.

25. In a slotted-screw system breech mechanism, the combination with the breech-block and a hinged carrier therefor, of means for rotating and withdrawing the block, consisting of a toggle-joint composed of swinging links, one of said links being extended and provided with a handle at one end and pivotally connected to the hinged carrier at the other end, and the other link being connected 100 to the first link about midway between the handle and pivotal point, and also connected directly to the breech-block at a point eccentric to the axis thereof, the members of the toggle-lever being so placed as to operate substantially 105 in the same plane, substantially as described.

26. In a slotted-screw system breech mechanism, the combination with a breech-block, of a toggle-joint having one of its members 115 composed of a single link with two screw-threaded pins swiveled thereto, the said pins being screwed to said breech-block eccentric to the axis thereof, and to the front of the second member, and the other member being pivotally 120 connected to the gun, or its attachments, the said toggle-joint being at or near the dead-center position when the breech is closed, whereby the said breech-block may be locked 125 in the gun, turned about on its axis, and moved inwardly and outwardly, substantially as described.

27. In a slotted-screw system breech mechanism, the combination with a breech-block and hinged carrier, of means for locking, rotating, and withdrawing the block, consisting 130 of a toggle-joint, one of the links of which is

in the form of a hand-lever attached to the hinged carrier, and the other composed of a single link with two screw-threaded pins swiveled thereto, the said pins being screwed 5 into the breech-block at a point away from its axis and into the hand-lever, respectively, substantially as described.

In testimony whereof I affix my signature in presence of two witnesses.

VERNON C. TASKER.
